Design No. 638.—
Samuel D. Vose.

Design for Coal Stoves.—

Patented 28. March 1854

Samuel D. Vose

Albany N.Y.

Feb. 1854

UNITED STATES PATENT OFFICE.

SAMUEL D. VOSE, OF ALBANY, NEW YORK.

DESIGN FOR A COAL-STOVE.

Specification forming part of Design No. 638, dated March 28, 1854.

To all whom it may concern:

Be it known that I, SAMUEL D. VOSE, of Albany, county of Albany, and State of New York, have invented a new and ornamental Design for a Coal-Stove; and I do hereby declare the following to be a full and exact description, reference being had to the annexed drawing, affixed to this specification.

The configuration which embodies the design cannot be easily described in words. The several plates which, when set up together, make up the design are referred to in the drawings by letters, as follows:

Letter L represents the leg of the stove; B, the bottom of the stove; E, the front of the base of the stove; S, the side of the base of the stove; L T, the top of the base of the stove;

F, the semi-cylindrical front of the stove; P, the posts or columns of the stove at the joint; U T, the upper top of the stove; C, the cover of the stove.

I do not claim any separate ornament upon either of these plates or parts.

What I claim as my invention, and desire to secure by Letters Patent, is—

The combination and arrangement of the several figures and moldings, the whole forming an ornamental design for a stove, as herein described.

SAML. D. VOSE.
